UNITED STATES PATENT OFFICE.

JOHN KINGSBURY, OF ALBANY, NEW YORK.

DESIGN FOR A LANDAU-SLEIGH.

SPECIFICATION forming part of Design No. 17,631, dated August 16, 1867.

Application filed April 2, 1867. Serial No. 233,466. Term of patent 7 years.

To all whom it may concern:

Be it known that I, JOHN KINGSBURY, of the city and county of Albany, and State of New York, have invented and produced a new and original Design for Landau-Sleighs, of which the following is a full and clear description, reference being had to the accompanying photographic illustrations, which form part of this specification, and in which—

10 Figure 1 is a side perspective view of my new landau-sleigh; Fig. 2, an angular perspective view of same, showing the front and one side; and Fig. 3, an angular perspective view showing the back and one side.

15 Heretofore the bodies of both landau and barouche sleighs have had their quarter-panels, belts, and cheek-pieces carried in a continuous unbroken line from the rearmost end of the body to the bracket or foot-board under 20 the dickey-seat, and the effect produced by such a design has been to give to the sleigh an unnecessarily heavy and cumbersome appearance.

25 In my new design for landau-sleighs the special features are, first, the body of the sleigh having the appearance of two distinctive parts, the after or main-body part being of greater width than the forward extension, whereon the driver's seat is located, the line 30 of division between the two parts being a definitive shoulder, which has the form of a coupé-pillar; and, second, an ornamental scroll-work which is interposed between the upper line of the runners and the lower line of the body, as shown in the illustrations and herein described.

35 As represented in the illustrations, A indicates the runners of the sleigh, which curve upwardly at their forward part and are carried in an approximately-straight line to their upper ends, which terminate in an ornamental head, 1.

40 B is the main body of my landau-sleigh, which, unlike those of prior design, does not extend the full length of the runners in an unbroken panel. The sides of said main body have the usual outer swell that is given to the bodies of sleighs, and the rearmost end of said body has an outwardly-curved outline, 4, which as it is carried forward is modified into a flatter curve, 5, that is carried to the forward end of said main body and at the point 6 meets a reversed curve or concave

line, 7, which is carried upwardly to meet and be merged into an approximately vertical 55 straight line, 8, that is carried to the top of said main-body part, thereby forming in effect a coupé-pillar, b, at that part of the body.

The lower quarter-panel, C, is bordered on its lower side by the ravel-molding c and at 60 its forward end by the molding c', and the lower and forward outline of said quarter-panel follows the contour of the outline of the body at those parts. The upper outline of said quarter-panel is formed by the lower edge 55 of the belt D, whereby an easy concave line is given to said upper outline, and the latter, by meeting the ravel-molding c at the rearmost end of said quarter-panel, forms a pointed terminal, c'', at that part. The belt D extends forward from the rearmost edge of the side of the main body to the foremost edge of the same, and the lower outline of said belt is formed by an easy convex line, 9, and its upper outline by a quicker curve of concave line 10 or 75 compass-sweep, whereby a gradual increase in width is given to said belt toward its forward end.

The upper quarter-panels, E, of which there are two, and the door-panel E' have their lower 80 outline formed by the upper edge of the belt D, and the upper outline of said panels is an approximately straight line, 11, which extends across the side of the body and forms a finishing-line for the flexible sides of the landau-top, 85 which sides extend forward and rearward from the opposite sides of the opening for the door F. The latter has a crest or monogram panel, f, near its upper end. The rocker G, which forms the sunken bottom of the main body B, 90 begins with a sharp edge at the point 6, and its lower edge is curved downwardly by the convex line 12, whose curvature is gradually lessened toward the forward side of the opening for the door F, from whence it follows 95 nearly a horizontal line to the shoulder 13. A few inches beyond the rearmost side of said door-opening from the shoulder 13 the lower edge of said rocker is deflected upwardly by the concave line 14 until it is brought nearly 100 to the convex outline of the back of the main body B. The back of said body is carried upward by a semi-elliptical outline, 15, above the sides of said body. Said back has a sunken panel, 16, formed therein, and the lower edge 105 of said panel is made on a straight line that

Open

coincides with the rearmost end of the rocker G, and the lower part of the back conforms to the hollow of the concave line 14 of the rocker.

The door F is carried through the upper and lower quarter-panels, belt D, and rocker G, but is finished to present a uniform appearance with said parts. The forward extension H of the main body B is integral with the latter, but is of less width, thereby leaving a bold shoulder at each side where the forward extension and main body join together. The lower side of said forward extension is raised a few inches above the lower edge of the front of the main body, and the neck h of said extension is quite shallow, as shown in Fig. 1. The lower edge of the side of said forward extension nearest the main body B is formed by a concave line, 17, which at first rises slightly and then curves downwardly to meet a straight horizontal line, 18, that is underneath the dickey-seat. The last-named line joins an upwardly-inclined line, 19, that forms the lower edge of the bracket or foot-board J. The upper edge of the forward extension nearest the main body B is formed by a concave line, 20, which curves upwardly to meet the straight horizontal line on which the dickey-seat K is located. In front of the latter the concave line 21 sweeps downwardly and dies in an upwardly-inclined straight line, 22, at the upper edge of the bracket J. The cheek-piece panel L is formed by the upper edge of the belt M, the bead m at the edge of the line 20, the lower side of the dickey-seat K, and molding m' at the edge of the line 21. The paneled dash-board N at the front end of the bracket J has at each end side wings, n, which are rounded at their upper and lower ends. Arches 23 appear above the wings n, and a rectangular panel, 24, above the dash-board N.

An ornamental scroll is interposed between the lower line of the body and the upper line of the lower part of the runners, which scroll extends from near the forward end of each runner to the rear end of the same. Said scroll-work consists of a continuous scroll that is composed as follows: An open circle, 25, reaches from the upper side of the runner A to the underside of the forward extension, H, joining to the latter at the line 18 under the dickey-seat K. A scroll, 26, extends forward from the circle 25 to the forward part of the runner, and is then bent back to the under side of the bracket J. Another scroll, 27, extends from the after side of the circle 25, and, after being carried upward to the forward part of the rocker G, is curved downward to join to a similar part of the succeeding scroll, and is so continued until its terminal joins the upper side of the runner. Next in succession is a horizontally-arranged S-shaped scroll, whose upper end joins the under side of the rocker G just in front of the forward side of the door F. The foremost turn, 28, of said scroll, in being carried forward, is curved downward, and, after forming a junction at X with the scroll 27, joins the upper side of the runner.

A continuation of said scroll forms an ogee line, 29, which extends rearward and upward to its point of contact with the under side of the main body near the after side of the door F. From that point the rearmost turn, 30, of said scroll curves downward, forming a junction at Y with the scroll 31, and then forward until it is secured to the upper side of the runner. The upper end of the scroll 31 joins the rear part of the rocker G at the curved line 14, and in passing slightly forward is curved downward to join the curve 30 at Y, and is then curved rearward and downward to meet the upper side of the runner, which it joins, and is then curled to form the terminal 32.

What I claim as new, and desire to secure by Letters Patent, is—

1. In a design for a landau-sleigh herein described and shown, the shape and configuration of the main body B and forward extension, H, the first being defined by the convex lines 4 and 5, concave line 7, vertical line 8, and horizontal line 11, and the other being defined by the concave lines 17, 20, and 21, horizontal line 18, inclined lines 19 and 22, and dickey-seat K, as herein specified.

2. In a design for a landau-sleigh herein described and shown, the ornamentation of the side of the main body B, consisting of the lower quarter-panel, C, as defined by the ravel-molding c, forward molding, c', and lower line, 9, of belt D, the belt D as defined by the convex line 9 and concave line 10, and the upper quarter-panels, E and E', as defined by the upper line, 10, of belt D, vertical line 8, and horizontal line 11, as herein specified.

3. In a design for a landau-sleigh herein described and shown, the shape and configuration of the rocker G, as defined by the point 6, convex line 12, shoulder 13, and concave lines 5 and 14, as herein specified.

4. In a design for a landau-sleigh herein described and shown, the shape and configuration of the dash-board N, whose side wings, n, are rounded at the upper and lower ends, the arches 23, and panel 24, as herein specified.

5. In a design for a landau-sleigh herein described and shown, the shape and configuration of the scroll-work composed of the open circle 25, scrolls 26, 27, 28, 30, 31, and 32, and ogee line 29, as herein specified.

6. In a design for a landau-sleigh herein described and shown, the shape and configuration of the main body, forward extension, and scroll-work, said main body being defined by the convex lines 4 and 5, concave line 7, vertical line 8, and horizontal line 11, said forward extension by the concave lines 17, 20, and 21, horizontal line 18, inclined lines 19 and 22, and dickey-seat K, and said scroll-work by the open circle 25, scrolls 26, 27, 28, 30, 31, and 32, and ogee line 29, as herein specified.

JOHN KINGSBURY.
